(57) **CLAIM**

The ornamental design for a detergent pouch, as shown and described.

DESCRIPTION

The patent or application file contains at least one drawing executed in color. Copies of this patent or patent application publication with color drawing(s) will be provided by the Office upon request and payment of the necessary fee.

FIG. 1 is a front perspective view of a first embodiment of detergent pouch embodying my new design;

FIG. 2 is a front side elevation view thereof;

FIG. 3 is a rear side elevation view thereof;

FIG. 4 is a right side elevation view thereof;

FIG. 5 is a left side elevation view thereof;

FIG. 6 is a top plan view thereof; and,

FIG. 7 is a bottom plan view thereof;

FIG. 8 is a front perspective view of a second embodiment of a detergent pouch embodying my new design;

FIG. 9 is a front side elevation view thereof;

FIG. 10 is a rear side elevation view thereof;

FIG. 11 is a right side elevation view thereof;

FIG. 12 is a left side elevation view thereof;

FIG. 13 is a top plan view thereof; and,

FIG. 14 is a bottom plan view thereof.

The broken lines are included for the purpose of illustrating the portions of the detergent pouch that form no part of the claimed design. The unshaded areas adjacent to the broken lines depict portions of the detergent pouch that form no part of the claimed design.
